United States Patent Office

Des. 214,964

Patented Aug. 12, 1969

214,964

FLASHING SIGNAL UNIT

Robert D. Kahn, 24 Maple Ave., Rockville
Centre, N.Y. 14609

Continuation-in-part of design application Ser. No. 9,385,
Nov. 13, 1967. This application May 23, 1968, Ser. No.
12,055

Term of patent 14 years

Int. Cl. D29—99

U.S. Cl. D72—1

FIG. 1

FIG. 2

FIG. 3

FIG. 1 is a perspective view of the design for a flashing signal unit;

FIG. 2 is a front elevational view thereof; and

FIG. 3 is a bottom plan view thereof.

This is a continuation-in-part of application Ser. No. D. 9,385, filed Nov. 13, 1967, now Design Patent D. 212,722.

I claim:

The ornamental design for a flashing signal unit, as shown.
